(57) **CLAIM**

The ornamental design for a drinking vessel, as shown and described.

DESCRIPTION

FIG. 1 is a top perspective view of our new design for a drinking vessel.

FIG. 2 is a top plan view thereof.

FIG. 3 is a bottom plan view thereof.

FIG. 4 is a front elevation view thereof.

FIG. 5 is a rear elevation view thereof.

FIG. 6 is a right side elevation view thereof.

FIG. 7 is a left side elevation view thereof.

FIG. 8 is an exploded view thereof.

FIG. 9 is a top perspective view of the lid portion of our new design, shown separately for clarity of disclosure.

FIG. 10 is a top plan view thereof.

FIG. 11 is a bottom plan view thereof.

FIG. 12 is a front elevation view thereof.

FIG. 13 is a rear elevation view thereof.

FIG. 14 is a right side elevation view thereof.

FIG. 15 is a left side elevation view thereof.

FIG. 16 is a cross-sectional view of the lid taken along line 16-16 in FIG. 12; and,

FIG. 17 is a cross-sectional view of the lid taken along line 17-17 in FIG. 4.
